UNITED STATES PATENT OFFICE.

JOHN MANGER, OF LONDON, ENGLAND.

SCHOOL-SLATE.

SPECIFICATION forming part of Letters Patent No. 332,095, dated December 8, 1885.

Application filed August 18, 1885. Serial No. 174,722. (No model.) Patented in England June 19, 1885, No. 7,480.

To all whom it may concern:

Be it known that I, JOHN MANGER, watch-manufacturer, a subject of the Queen of Great Britain, and a resident of London, England, 5 have invented new and useful Improvements in and relating to Slates for Educational Purposes, (for which I have applied for provisional protection in Great Britain, No. 7,480, bearing date June 19, 1885,) of which the following is 10 a specification, reference being had to the accompanying drawings.

My invention relates to slates for educational purposes; and it consists, chiefly, in providing such slates with rulers adapted to slide 15 thereon, whereby lines may be readily drawn in one or the other direction, as desired.

In the accompanying drawings, Figure 1 is a front elevation of an educational slate provided with improvements according to this invention. Fig. 2 is an edge view of the same, and Fig. 3 is a section on the line $x x$, Fig. 1.

Similar letters of reference indicate the same parts in all the figures.

a indicates a slate, the frame of which is 25 composed of two side strips, $b b$, and two end strips, $c c$, in a well-known manner.

d indicates the ruler, which slides upon the side strips, $b b$. This ruler is composed of two bars, $e e$, one upon each side of the slate, 30 and two connecting-pieces, $f f$, to which the bars $e e$ are attached, so as to slide freely upon the frame. The two pieces $f f$ are made considerably longer than the width of the bars $e e$, as shown in Fig. 1, in order to prevent the 35 ruler from getting out of a horizontal position, and so sliding stiffly or becoming immovable.

$g g$ are pieces which are attached to the end strips, $c c$, of the frame at either side. These end pieces serve to prevent the ruler from being slipped off the slate-frame, and also serve 40 to protect the ruler when not in use. The extended ends of the connecting-pieces $f f$ are adapted to enter between the projecting ends of the pieces $g g$, so that the ruler can be 45 moved close to the top and bottom of the slate. Instead of attaching strips g , as described, the parts $c c$ of the frame may be made of sufficient thickness to render this unnecessary.

With the ruler arranged as described, it will 50 be seen that horizontal parallel lines can be ruled upon both sides of the slate.

In order to enable lines to be drawn at right angles to the horizontal lines—for instance, for money-columns—holes $h h$ are formed in one or both bars of the ruler, as shown in dotted lines in Figs. 1 and 2, so that by placing a pencil in one of these holes and drawing the ruler in a downward direction the desired lines can be drawn. Any desired number of these holes can be formed in one or both sides of the ruler. 55 Slots are sometimes formed in the said strips in lieu of holes, the said slots extending the whole width of the slate, and being provided with notches upon their edges to prevent the pencil from slipping. 60

In some instances the edge of the slate and the ruler are graduated to a scale of measurement, as shown in Fig. 1, so as to enable lines to be drawn at regular or other desirable distances apart. This is very useful for drawing 70 maps, as the lines of latitude and longitude can be quickly drawn.

The sliding ruler is of special advantage in teaching children to write, as the copy may be placed upon the ruler and the latter moved 75 downward one line each time a line of writing is completed, so that the child sees the copy which he has to imitate just above the line upon which he is writing, and therefore is not so liable to make mistakes and such imperfect copies (by copying the line immediately above which he has written himself) as is the case when the copy is fixed at the top of the slate.

In order to enable the copy to be held to the 85 ruler, the latter is provided upon one or both sides with metal clips $i i$, between which and the ruler the copy is slipped. These clips are preferably secured by rivets or screws $j j$, which also serve to connect the bars $e e$ and 90 pieces f .

I sometimes provide for ruling lines at any angle to the horizontal lines. For this purpose one or both of the strips e may have a second strip, k , of the same size as itself, pivoted 95 thereto at one end, which strip is adapted to be placed at a greater or less angle to the ruler, as shown by dotted lines in Fig. 1.

It is obvious that I may modify the construction hereinbefore described without departing 100 from the nature of my invention; for instance, instead of making the ruler in four pieces, as

described, it may be made in one piece, a slot being formed of sufficient size to enable the said ruler to slide upon the frame; also, instead of the ends *ff* of the ruler sliding upon the edges of the side pieces, *bb*, they might be arranged to slide in longitudinal slots formed therein.

What I claim is—

1. The combination, with a slate, of a ruler mounted upon slides which move upon the parallel sides of said slate, and spring-clips mounted upon both ends of said ruler and substantially in the central longitudinal line thereof, and bearing upon the flat surface thereof, whereby a copy may be held flat upon and moved with said ruler, substantially as described.

2. The combination, with a slate having a scale of measurement marked upon one of its parallel sides, of a ruler consisting of a double

strip united at both ends and sliding upon the parallel sides of the slate, and clips mounted upon each end of the ruler to receive and hold a copy, substantially as described.

3. The combination, with a slate having a ruler, *d*, sliding upon its parallel sides, of a strip, *k*, pivoted upon said ruler near one end, substantially as described.

4. The combination of the slate *a*, having a scale of measurement marked upon the frame thereof, the strips *g*, with the ruler *d*, having a scale of measurement marked thereon, and the clips *i*, substantially as described.

In testimony whereof I have hereunto signed my name in the presence of two subscribing witnesses.

JOHN MANGER.
